UNITED STATES PATENT OFFICE.

SØREN MADSEN, OF PERTH AMBOY, NEW JERSEY.

SLOT-MACHINE.

1,116,599.

Specification of Letters Patent. Patented Nov. 10, 1914.

Application filed November 13, 1913. Serial No. 800,842.

To all whom it may concern:

Be it known that I, SØREN MADSEN, a subject of the King of Denmark, residing at Perth Amboy, in the county of Middlesex and State of New Jersey, have invented certain new and useful Improvements in Slot-Machines; and I do hereby declare the following to be a full, clear, and exact description of the invention, such as will enable others skilled in the art to which it appertains, to make and use the same, reference being had to the accompanying drawings, and to the letters and figures of reference marked thereon, which form a part of this specification.

This invention relates to new and useful improvements in slot machines for dispensing commodities, etc., and comprises a simple and efficient device of this nature having various details of construction and combinations and arrangements of parts which will be hereinafter fully described, shown in the accompanying drawings and then specifically defined in the appended claims.

My invention is illustrated in the accompanying drawings, in which:—

Figure 1 is a top plan view of my improved slot machine. Fig. 2 is a sectional view transversely through the apparatus. Fig. 3 is a cross sectional view on line 3—3 of Fig. 1. Fig. 4 is a sectional view on line 4—4 of Fig. 2. Fig. 5 is a sectional view taken on line 5—5 of Fig. 2 showing the locking bolt. Fig. 6 is a similar view taken on line 6—6 of Fig. 4. Fig. 7 is a detail section on line 7—7 of Fig. 4, and Fig. 8 is a detail perspective view of the locking latch.

Reference now being had to the details of the drawings by letter, A designates a cylindrical casing with coin slot A² and having a disk B with radial arms which are fastened to the wall of the casing near the lower edge thereof and which disk has journaled therein the rotatable post C which also has a bearing in the top A' of the casing. Said top has a series of radially disposed lid openings A³, covered preferably by glass in order to disclose the commodities to be vended and which are contained within the compartments C^x of the wheel C', which latter is provided with a central cylindrical portion D and has radial partitions E forming the compartments which are open at their outer ends and which compartments are accessible through the opening F con-

trolled by the sliding door F'. Said door is guided in its longitudinal movements by the strips F² and an angled bar, one arm F³ of which is fastened to said door and is provided with a coin slot F⁵ therein, while the long arm F⁶ of said angle bar is preferably curved to conform to the cylindrical outline of the casing and is recessed upon its under edge at F⁷ for a purpose which will be hereinafter described. Said angle bar has a notch F⁸ formed in the under edge thereof adjacent to one end and which is adapted to be engaged by the laterally projecting lug G upon the tilting latch G', which latter is pivotally mounted upon a pin G² carried by the casing.

A spring H is fastened to the casing and bears against one end of said latch and serves to normally hold the lug G in said notch and serves to lock the door closed. A second lug, designated by letter G³, projects from said latch and has a slot G⁴ in its upper edge in which the coin which is used to operate the apparatus rests and which coin is designed to cause the latch to be depressed to throw the lug G at the end thereof out of the notch F⁸ to allow the door to open when the operator grips the handle thereon, causing the door to slide back between the guiding strips referred to. The door is returned to its normal position through the medium of the spring I which is fastened at I' to the casing, being protected by a housing I² and its other end fastened to a tilting bar I³ which is pivoted at I⁴ to the casing and engages one end of a slot J formed in said angle bar.

The means for imparting an intermittent movement to the compartment wheel whereby the compartments are brought successively to register with the door opening consists of a ratchet wheel K fixed to said post and provided with a flange K' upon its under surface, having notches K² at intervals, one for each compartment of the wheel. An angle bar, designated by letter L, is mounted to have a sliding longitudinal movement in the slots M of the bracket arms M' which are fastened to the plate M² fixed to the arms of said disk. Said angle bar L is given a longitudinal movement in one direction by the pull rod N guided in an aperture a in the casing and provided with a handle N' at one end and has a recess L³ in the upper edge thereof which is adapted

to receive the long arm F⁶ of the first referred to angle bar to prevent the pull rod being operated while the door is opened.

A coiled spring Q is fastened at one end to 5 the casing and its other end to the angle bar L and co-operates with a piston rod Q² fastened to a plunger within the pump cylinder Q³ to return the angle bar L to its normal position after having been moved forward 10 by said pull rod. A pawl, designated by letter Q⁶, is pivotally mounted upon the angle bar L and is held by means of a spring R' in engagement with the teeth of the ratchet wheel and serves to impart an intermittent movement to said wheel, which is fastened to the compartment wheel, each 15 time the angle bar L is returned to its normal starting position. In order to lock the compartment and ratchet wheels from rotation when the apparatus is at rest, a longitudinally movable bolt, designated by letter S, which is mounted to move through slots 20 in the bracket arm S' fastened to the plate M², is thrown into engagement with one or another of the slots in the flange of the ratchet wheel through the medium of the spring R², fastened at one end to the bracket member and the other end to one end of a pin R⁴ which is fastened to said bolt, the 25 other end of the pin being adapted to engage the cam or inclined edge of the bar L when the latter is moved forward by the pull bar. Said cam edge of the bar L, it will be noted, will hold the bolt out of the slots 30 until the bar L returns to its normal position, after which the bolt will be thrown by the spring attached thereto into one of the slots and hold the wheels from rotation.

The operation of my invention is as follows:—When it is desired to dispense any commodity from the apparatus, the operator may bring one or another of the compartments in the rotatable wheel so that one particular compartment will register with 45 the opening normally closed by the sliding door. This is accomplished by the pulling out upon the pull rod which will cause the angle bar L to be drawn forward under the tension of the spring and the suction upon 50 the piston within the air pump, the rod of which is pivotally connected to said bar L, the spring-pressed pawl turning idly over a single tooth of the ratchet wheel. When the operator releases the pull rod, the spring and 55 piston within the pump will cause the angle bar L to return to its normal position and the pawl which engages the teeth of the ratchet wheel will cause an intermittent movement to be imparted to the ratchet and 60 compartment wheels. In the outer movement of the pull rod, the cam edge of the angle bar L coming in contact with the pin upon the bolt will cause the latter to be pulled out of the retaining notch in the 65 flange upon the ratchet wheel so as to allow

the latter to make a partial revolution on the return movement of the bar L. When it is desired to remove the commodity from the opening closed by the sliding door, it will be necessary to drop a coin in the slot A², the same rolling down and engaging the slot in the lug G⁸ upon said latch, after which, when a person takes hold of the handle upon the door and pushes the same back, the coin will press against the latch and throw the lug at the end thereof out of the notch F⁸ and which will allow the door to open. When the door is open, the long arm F⁶ of said angle lever will engage the recess in the pull rod and will prevent the latter being pulled 70 out until the door is closed, which latter movement will throw the angle bar so that the groove in the under edge of the long arm F⁶ thereof will come adjacent to the pull bar and allow the same to be operated by an outward pull thereon. After the coin has been utilized to throw the latch out of a disengaging relation with the notch, it will fall by gravity in the latch and, when the door is closed, the spring which bears against the 75 latch will throw the lug at the end thereof in engagement with the notch in the angle lever and hold the same locked.

What I claim to be new is:—

1. A vending apparatus comprising a casing, a rotatable compartment wheel therein, a post upon which the same is mounted, a ratchet wheel fixed to said post and having a notched flange, a spring-pressed bar, a pull rod connected thereto, a pawl carried by said bar and adapted to engage the ratchet wheel and impart an intermittent movement to the latter on the return of the bar to its normal position, a spring-pressed bolt normally engaging the notched flange, 95 means for throwing the bolt out of engagement with the notches of the rim as the bar is moved in one direction, a door adapted, when open, to lock said pull rod, thereby preventing the wheel from rotation. 100

2. A vending apparatus comprising a casing, a rotatable compartment wheel therein, a post upon which the same is mounted, a ratchet wheel fixed to said post and having a notched flange, a spring-pressed bar, a notched pull rod connected thereto, a pawl carried by said bar and adapted to engage the ratchet wheel and impart an intermittent movement to the latter on the return of the bar to its normal position, a spring-pressed bolt normally engaging the notched flange, 115 means for throwing the bolt out of engagement with the notches of the rim as the bar is moved in one direction, a sliding door, the lower edge of which, when open, is adapted to engage the slotted pull rod to lock the same against longitudinal movement and thereby prevent the wheel from rotation. 120

3. A vending apparatus comprising a cas- 130

ing, a rotatable compartment wheel therein, a post upon which the same is mounted, a ratchet wheel fixed to said post and having a notched flange, a spring-pressed bar, a notched pull rod connected thereto, a pawl carried by said bar and adapted to engage the ratchet wheel and impart an intermittent movement to the latter on the return of the bar to its normal position, a spring-pressed bolt normally engaging the ratchet

10 pressed bolt normally engaging the notched flange, means for throwing the bolt out of engagement with the notches of the rim as the bar is moved in one direction, a door, the lower edge of which is adapted to move

15 through the notched pull rod to lock the rod when the door is open, the lower edge of the door having a notch positioned, when closed, in alignment with the rod to allow the same to move freely.

20 4. A vending apparatus comprising a casing, a rotatable compartment wheel therein, a post upon which the same is mounted, a ratchet wheel fixed to said post and having a notched flange, a spring-pressed bar, a

25 a hooked hinge, a spring pressed bar, a pull rod connected thereto, a pawl carried by said bar and adapted to engage the ratchet wheel and impart an intermittent movement to the latter on the return of the bar to its normal position, a spring-

30 the bar to its normal position, a spring-pressed bolt and mounting therefor and adapted to engage the notches of the flange, a pin projecting from said bolt, said bar having a cam edge designed to engage said pin to retract the bolt as the bar is moved.

pin to retract the bolt as the bar is moved longitudinally in one direction by the pull rod, a door to the casing designed, when open, to engage the notch in said pull rod to hold the same in a locked position to prevent the wheel from rotation.

40 5. A vending apparatus comprising a casting, a rotatable compartment wheel therein, a post upon which the same is mounted, a ratchet wheel fixed to said post and having a notched flange, a longitudinally movable

45 a notched hinge, a longitudinally movable angle bar, a spring fastened at one end to the casing and the other end to said bar, a

pneumatic cylinder with piston therein having a stem which is fastened to said bar, a spring-pressed pawl pivoted to the latter and adapted to engage the ratchet wheel, a spring-actuated bolt designed to engage the notches of the flange to hold the wheel stationary, means for throwing the bolt out of engagement with the flange when the bar is moved in one direction, a pull rod fastened to said bar, a door to the eas-ing designed, when open, to engage the notch in said pull rod to hold the same in a locked position to prevent the wheel from rotation.

6. A vending apparatus comprising a casing, a rotatable compartment wheel therein, a post upon which the same is mounted, a ratchet wheel fixed to said post and having a notched flange, a longitudinally movable angle bar having an aperture adjacent to one end thereof, a spring fastened at one end to the casing and the other end to said bar, a pneumatic cylinder with piston therein having a stem which is fastened to 70 said bar, a spring-pressed pawl pivoted to the latter and adapted to engage the ratchet wheel, a spring-actuated bolt designed to engage the notches of the flange to hold the wheel stationary, means for throwing 75 the bolt out of engagement with the flange when the bar is moved in one direction, a pull rod movable through an opening in the casing and having sliding connections with the aperture in said angle bar, allowing the latter to move independent of the rod, a door to the casing designed, when open, to engage the notch in said pull rod to hold the same in a locked position to prevent the wheel from rotation. 80 85

In testimony whereof I hereunto affix my signature in presence of two witnesses.
